CLAIM

The ornamental design for an aerosol can stand, as shown and described.

DESCRIPTION

FIG. 1 is a top plan view of an aerosol can stand showing my new design;

FIG. 2 is a side view thereof;

FIG. 3 is an isometric view thereof; and,

FIG. 4 is an isometric view thereof illustrating an aerosol can being positioned therein.

The broken lines shown in FIG. 4 depict environmental subject matter only and form no part of the claimed design.
